UNITED STATES PATENT OFFICE.

JULIUS E. NACHOD, OF PHILADELPHIA, PENNSYLVANIA.

ENVELOP-SEALING MACHINE.

No. 829,030.

Specification of Letters Patent.

Patented Aug. 21, 1906.

Application filed May 17, 1906. Serial No. 317,266.

To all whom it may concern:

Be it known that I, JULIUS E. NACHOD, a citizen of the United States, residing in the city and county of Philadelphia, State of Pennsylvania, have invented certain new and useful Improvements in Envelop-Sealing Machines; and I do hereby declare the following to be a full, clear, and exact description of the invention, such as will enable others skilled in the art to which it appertains to make and use the same.

The invention relates to apparatus for sealing envelops, and belongs generally to that type of envelop-sealing machines described and claimed in Letters Patent granted to me March 27, 1906, and numbered 816,175 and 816,176, respectively, and has for its objects to improve the means for moistening the flaps of the envelops as they pass through the machine, as well as the means for pressing the flaps against the body of the envelops as the latter are discharged from the machine, said improvements being particularly adapted to machines of this general type.

In the accompanying drawings, Figure 1 is a perspective view of the apparatus. Fig. 2 is a plan view thereof, the top plate being partially broken away. Fig. 3 is a longitudinal section on the irregular line 3 3, Fig. 2.

Referring to the drawings, *a* indicates the casing of the apparatus, which may be conveniently constructed, as in my prior patents hereinbefore referred to, said casing consisting of a base *b*, side and end walls, and a top constituting a platform *e*, over which the body of the envelop is passed. The side wall *i* on the left of the casing serves to guide the flap as it enters the machine and hold the same with its gummed side in engagement with the moistening device. Between the side wall *i* and the end wall *l* of the casing there is provided a guide-wall *k*, having a surface twisted or skewed both longitudinally and transversely, so that said guide-wall springing from the side wall *i* gradually merges into a plane parallel with that of the platform *e*, whereby as the envelop is drawn across the platform *e* the flap after having been passed over the moistening device is engaged by the twisted or skewed guide-wall *k* until it is brought into substantial parallelism with the body of the envelop, from which it is separated by the thickness of the platform *e*.

Inasmuch as a stationary wick-like

tender tended to impede the passage of the envelop-flap through the machine, owing to the frictional drag, and also tended to become clogged by the deposit of gum on the felt, it was found expedient to provide a moistening device for the flap which would obviate both of these difficulties. This has been accomplished by providing as a moistening device a vertical roll consisting of a shaft *b'*, journaled in the platform *e* at one end and in a bearing located on the bottom of the reservoir *e'* at the other, a core *c'*, secured to the said shaft, and a pad of absorbent material—viz., felt or the like—surrounding said core and dipping into the reservoir. Said reservoir is conveniently formed as a closed pan *e'*, attached to the under side of the casing by suitable brackets *i'* and provided with a circular opening in its top, through which the moistening-roll extends, and adapted to receive a body of cotton fiber or similar absorbent material which holds sufficient water to keep the absorbent pad on the roll in the properly moist condition and nevertheless prevents the water spilling when the machine is moved. In order to supply the pan or reservoir with water, there is provided in the side of the base *b* a filling-opening *g'*, which communicates with the closed pan or reservoir *e'* and also serves as an overflow should too much water be supplied. The provision of the absorbent cotton within the reservoir leaves but little free water, yet provides moisture in sufficient quantity to supply the absorbent felt on the roller continuously, as demanded. Mounted on the inside of the wall *i* by means of suitable screws *n'* is a broad flat spring made of light sheet metal which presses against the moistening-roller, and as the flap of each envelop is caused to pass between said spring and the roller it will be apparent that the spring holds the flap in contact with said roller with just sufficient force to cause the flap to absorb the proper amount of moisture to soften the adhesive.

Should it be found necessary to remove the roller for adjustment or repair or renewal of the felt covering, it is necessary only to detach the reservoir, which will permit the roller to drop out of its bearings.

In order to avoid the tendency of the envelops to crease and buckle as they are discharged from the final sealing devices to accommodate envelops of various and varying thicknesses and also to facilitate the entry of the envelop between the coacting members

of the sealing or presser devices at the discharge end of the machine, I provide an especially efficient means for pressing the flap against the body to complete the sealing operation. This presser device consists of a bristle-brush *t*, mounted upon a metal spring *s*, which is attached to the cover-plate *n* of the machine by screws *u*, which spring is adjustable by means of a tension-screw *v*, engaging a nut *w* on the end of said spring and bearing against the cover-plate *n*. The bristle-brush *t* lies above and coöperates with a roller *r'*, mounted in brackets *q*, secured to the end plate *l* of the casing *a*, one of said brackets being somewhat longer than the other, so that the roller *r'* and the brush *t* coacting therewith lie at an angle to the direction of travel of the flap through the machine. The inclination of the roller to the direction of movement of the envelop insures the envelop passing gradually between the brush and the roller instead of moving abruptly into contact with the two pressing members, as in constructions heretofore produced, and which resulted in a high resistance and opposition to the movement of the envelop in the final sealing operation. The brush-bristles are arranged vertically and substantially radially to the roller, and they readily yield locally to such variations in thickness as would be occasioned by coins or other small irregular articles contained in the envelops. In order to hold the brush up to its work and prevent the bristles whipping backward, an auxiliary spring-plate *x*, attached to the under side of the brush-supporting spring *s*, engages the inner row of bristles near their lower ends. The brush coöperating with the roller exercises a more uniform pressure on the flap, and as this pressure is spread over a larger area than would be possible with the older form of presser mechanism the final operation of sealing is effected without wrinkling or creasing. By adjusting the tension of the spring *s* the degree of pressure between the brush and the roller may be regulated to the varying conditions of the work.

Having thus described my invention, what I claim, and desire to secure by Letters Patent, is—

1. In an envelop-sealing apparatus, the combination of a casing having a platform for supporting the body of the envelop, a lateral wall at an angle to the platform for guiding the flap, a moistening device adjacent to said lateral wall, a guide-wall for closing the flap on the body, a guide at the discharge end of the casing, and a brush coöperating with said guide to press the flap against the body.

2. In an envelop-sealing apparatus, the combination of a casing having a platform for supporting the body of the envelop, a lateral wall at an angle to the platform for guiding the flap, a moistening device adjacent

to said lateral wall, a guide-wall for closing the flap on the body, a guide-roller at the discharge end of the casing, and a brush coöperating with said guide-roller to press the flap against the body.

70

3. In an envelop-sealing apparatus, the combination of a casing having a platform for supporting the body of the envelop, a lateral wall at an angle to the platform for guiding the flap, a moistening device adjacent to said lateral wall, a guide-wall for closing the flap on the body, a guide at the discharge end of the casing, and a spring-pressed brush coöperating with said guide to press the flap against the body.

80

4. In an envelop-sealing apparatus, the combination of a casing having a platform for supporting the body of the envelop, a lateral wall at an angle to the platform for guiding the flap, a moistening device adjacent to said lateral wall, a guide-wall for closing the flap on the body, a guide at the discharge end of the casing, a spring-pressed brush coöperating with said guide to press the flap against the body, and means for adjusting the tension of said spring to vary the pressure between the brush and the guide.

85

5. In an envelop-sealing apparatus, the combination of a casing having a platform for supporting the body of the envelop, a lateral wall at an angle to the platform for guiding the flap, a moistening device adjacent to said lateral wall, a guide-wall for closing the flap on the body, a guide at the discharge end of the casing, and a spring-pressed brush coöperating with said guide to press the flap against the body, said guide and brush being set at an angle to the direction of travel of the envelop.

95

6. In an envelop-sealing apparatus, the combination of a casing having a platform for supporting the body of the envelop, a lateral wall at an angle to the platform for guiding the flap, a vertically-rotating moistening-roll adjacent to said lateral wall, a guide-wall for closing the flap on the body, and means for pressing the flap against the body.

105

7. In an envelop-sealing apparatus, the combination of a casing having a platform for supporting the body of the envelop, a lateral wall at an angle to the platform for guiding the flap, a vertically-rotating moistening-roll adjacent to said lateral wall, a reservoir beneath the casing for supplying moisture to said moistening-roll, a guide-wall for closing the flap on the body, and means for pressing the flap against the body.

115

8. In an envelop-sealing apparatus, the combination of a casing having a platform for supporting the body of the envelop, a lateral wall at an angle to the platform for guiding the flap, a moistening device comprising a vertically-rotating roll mounted adjacent to said lateral wall, an absorbent pad on said roll, a reservoir on the bottom of said casing

120

125

130

in which said pad dips, and means for pressing the flap against the body.

9. In an envelop-sealing apparatus, the combination of a casing having a platform 5 for supporting the body of the envelop, a lateral wall at an angle to the platform for guiding the flap, a moistening device comprising a vertically-rotating roll mounted adjacent to said lateral wall, an absorbent pad on said 10 roll, a reservoir on the bottom of said casing

in which said pad dips, a spring between the side wall and the moistening-roll to press the flap against said roll, and means for pressing the flap against the body.

In testimony whereof I affix my signature 15 in presence of two witnesses.
